UTENSIL KIT

William J. Forest, Eugene, Oreg.

Application October 21, 1946, Serial No. 704,662

3 Claims. (Cl. 30—142)

1

This invention relates to a utensil kit, and particularly to a kit where table utensils such as a knife, fork and spoon are held together as a kit in the handle of a can opener.

An object of the invention is to provide a compact unit in which the usual table utensils are securely held together in the handle of a can opener in such a manner that the utensils can be easily separated and removed for use, and can be quickly and securely assembled in a compact unit when out of use, without any danger of accidental separating or losing of utensils.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a development view of the can opener used as the container of my kit;

Fig. 2 is the completed unit of the can opener;

Fig. 3 is a spoon constructed for assembly in the kit;

Fig. 4 is a view of a fork constructed as part of the kit;

Fig. 5 is a side view of a knife constructed for assembly in my kit;

Fig. 6 is a side view of the can opener with its receptacle handle;

Fig. 7 is the kit assembled in the can opener; and,

Fig. 8 is a sectional view of the assembled utensils in the kit, the section being taken on the lines 8—8 of Fig. 7.

As shown in Fig. 1 the container of the kit is provided in a can opener which has the usual can opener head 1 and handle 2. The handle 2 has a back wall 3, side walls 4 and front walls 6. It is preferable that this can opener be made of a sufficiently firm material to operate as a can opener, for instance sheet metal of suitable gauge. Instead of the handle being made of sheet metal of heavier gauge it may be made of lighter gauge

and obtain its necessary rigidity as a handle by the folding of the developed handle as shown in Fig. 1, into the shape as Fig. 2, namely, in a box form, wherein the joining edges 7 of the front wall sections 6 are integrally united together by spot welding or the like suitable method. This box structure of the handle provides suitable rigidity and at the same time it provides a receptacle or pocket into which the other utensils can be placed. The bottom of this handle pocket is closed by the bottom flap 8 as shown in Fig. 1 and the top of the pocket is open alongside the front of the can opener head 1. The edges of said bottom flap 8 are preferably spot welded to the lower edges of the vertical walls of the hollow handle.

Fig. 1 also shows the forming of the can opener head, so as to have on the same the usual can and bottle openers and other apertures as necessary. The particular features connected with the present invention so far as the can opener head 1 is involved, are a side flap or flange 9 which is folded from the position shown in Fig. 1 forwardly as shown in Fig. 2 in substantial alignment with one of the sides 4 of the box handle and spaced above 15 the same. The purpose of this side flange 9 on the can opener head 1 is to align the utensils in the pocket of the box handle of the can in the proper position. A prong 11 on the top edge of the can opener head 1 is bent from the position 20 shown in Fig. 1 to the position shown in Fig. 2 and Fig. 6 so as to extend over the area of the pocket in the box-like can opener handle and is spaced above the same for interlocking engagement with 25 one of the utensils in a manner hereinafter described.

In the back wall 3 and spaced from the top edge of the box handle of the can opener is provided a button like depression 12 which appears as a slight dent 13 on the outside face of the rear 30 wall 3.

One of the utensils of the kit is a spoon 14, which is of the usual shape excepting that its handle 16 is flat and it is provided with a button and dent 17 so that the convex or button side 45 thereof can engage the dent 12 in the can handle while the other or the convex side thereof can be engaged in turn by the button of the next superimposed utensil. The handle 16 may be made of material of slightly heavier gauge than the spoon itself. The spacing of the button and dent 17 from the lower edge 18 of the spoon handle 16 is the same as the spacing of the dent 12 from the bottom 18 of the can handle in the assembled 50 position.

Another utensil in the kit is a fork 19, which is

also provided with a flat handle 21 which latter has on it a dent to form a concavo-convex button 22 in the manner heretofore described in connection with the spoon handle 16, which button 22 is spaced from the bottom edge 23 of the fork handle 21 the same distance as the spacing of the button 17 from the bottom edge 18 of the spoon handle 16.

Another utensil in the kit is a knife 24, which also has a flat handle 26. A concavo-convex button 27 on this knife is spaced from the lower edge 28 of the knife handle 26 in the same way as the respective spacings of the buttons 17 and 22 from the respective lower edges 18 and 23 of the spoon handle 16 and the fork handle 21. In this manner when the handles of the three utensils, the spoon, the fork and the knife are placed in superimposed relation in the pocket formed by the box can handle heretofore described, the buttons 17, 22 and 27 interengage with one another. The spoon button is engaged with the dent 12 in the back wall 3 of the can handle. In addition, on the back edge of the knife 24 is provided a notch 29 which is spaced in the same relation to the dent button 21 on the knife handle, as the spacing and offset relation of the prong 11 is with respect to the dent 12 in the can opener handle.

In operation the spoon is first placed in the pocket of the can opener handle adjacent to the back wall 3 so that the lower end 18 of the spoon handle rests upon the bottom 8 of said pocket. Then the fork is placed in the pocket so that the fork handle is superimposed upon the spoon handle 16 and its button 22 is in engagement with the concave side of the button 17 of the spoon handle 16. Finally the knife handle is placed in the pocket in the manner shown so that its button 27 is interengaged with the concave side of the button 22 of the fork handle 21, and the notch 29 on the back edge of the knife blade is in engagement with the prong 11 of the can head. This prong 11 extends substantially at right angles to the plane of the can head 1 so that it prevents lateral displacement of the knife. The disengagement of the knife blade or the notch 29 from the prong 11 is prevented by the retaining flange 9 on the can head which prevents sidewise displacement of the knife and the knife blade. The interlocking of the buttons 12, 17, 22 and 27 effectively hold the handles of the utensils together, while the engagement of the knife blade between the retaining flange 9 and the prong 11 of the can head, and the engagement of the prong 11 with the notch 29 in the knife edge prevents the sliding of the knife out of the pocket. In this manner the knife is effectively held in place and locks the remaining utensils together preventing accidental displacement or loosening of the various utensil sets used at picnics or in military kits or other portable uses where compactness is very important and where the separation and loosening of the individual utensils otherwise would cause a great deal of inconvenience. The device is very simply put together or disassembled for use. It does not require any adjustment or any clamping structures; by merely inserting the elements in the aforesaid superimposed relation, the knife, fork and spoon are securely held in the pocket of the can opener handle. At the same time the handles and parts of these utensils are of sufficient strength for their respective purposes and uses.

I claim:

1. In a utensil kit of the character described,

a can opener, a head on the can opener, a hollow handle open toward the head of the can opener, a plurality of utensils having handles slidably fitting into said hollow can opener handle, said can opener handle and said utensil handles having interlocking concavo-convex buttons thereon for holding said utensils together in said hollow handle, a prong extended from the head of the can opener, one of said utensils having a notch on one side thereof spaced the same distance from the end of the handle of said last utensil as the spacing between said prong and the lower end of the can opener handle, said notch being engaged by said prong for holding said last utensil in position to retain the other utensils in the can opener handle, and an aligning flange on the can opener spaced from said prong and being substantially opposite the other side of said last utensil.

2. In a utensil kit of the character described, a can opener, a hollow handle on the can opener having a bottom at the end of the handle and being open at the top near the operating head of said can opener, said handle being of rigid box-like construction, a spoon, a fork and a knife, a substantially flat handle on each, said spoon, said fork and said knife, slidably fitting in superimposed relation into said pocket of said handle, said spoon being placed closest to the operating head of the can opener, said fork being superimposed on said spoon and said knife being closest to the outer wall of said pocket, a prong extended from the head of said can opener, said knife having a notch in the edge thereof spaced the same distance from the end of the handle of said knife as the spacing between said prong and the lower end of said can handle and being engaged by said prong for holding said knife in position to retain said spoon and fork within said hollow handle, and an aligning flange on said can opener handle spaced from said prong and being substantially opposite the other edge of said knife.

3. In a utensil kit of the character described, a can opener, a hollow handle on the can opener having a bottom at the end of the handle and being open at the top near the operating head of said can opener, said handle being of rigid box-like construction, a spoon, a fork and a knife, a substantially flat handle on each, said spoon, said fork and said knife, slidably fitting in superimposed relation into said pocket of said handle, said spoon being placed closest to the operating head of the can opener, said fork being superimposed on said spoon and said knife being closest to the outer wall of said pocket, a prong extended from the head of said can opener, said knife having a notch in the edge thereof spaced the same distance from the end of the handle of said knife as the spacing between said prong and the lower end of said can handle and being engaged by said prong for holding said knife in position to retain said spoon and fork within said hollow handle, and an aligning flange on said can opener handle spaced from said prong and being substantially opposite the other edge of said knife, each said hollow can handle and said handles of the spoon, fork and knife having a concavo-convex button in the handle of each thereof equally spaced from the ends of the respective handles for interengagement when said utensils are assembled in said hollow handle.

WILLIAM J. FOREST.
